Primary Examiner — Elizabeth J Oswecki

(74) Attorney, Agent, or Firm — Banner & Witcoff, Ltd.

(57) CLAIM

The ornamental design for a shoe, as shown and described.

DESCRIPTION

FIG. 1 is a photographic side view of a shoe showing my new design;

FIG. 2 is a front perspective view thereof; and,

FIG. 3 is a front perspective view of the claimed region as shown in FIG. 2 with disclaimed environment removed for clarity purposes.

The dark portions of the entire shoe upper, outsole toe and heel portions of the shoe shown in FIGS. 1 and 2 that have been embraced in a long dash short dash long dash broken line show portions of the shoe that form no part of the claimed design.
